UNITED STATES PATENT OFFICE

JOSEPH EDWIN BURGESS, OF NEW YORK, N. Y., ASSIGNOR TO THE UNITED STATES PRINTING & LITHOGRAPH COMPANY, OF BROOKLYN, NEW YORK, A CORPORATION OF OHIO

DISPLAY TOY AEROPLANE

Application filed June 20, 1928. Serial No. 286,973.

My invention relates to toy aeroplanes and has for its primary object to provide a toy aeroplane which can be economically made of a sheet of paper or cardboard for convenient packing and transportation and when assembled will form an attractive miniature of an aeroplane of a well-known type which can be advantageously used for advertising purposes.

- 10 To this end my invention, in its present preferred form, consists generally of a blank or sheet with a transverse wing portion at one end, a longitudinal neck portion with a head portion projecting medially from the wing portion, and combination tail and fuselage portions projecting laterally and oppositely from the terminal head portion, so that the tail and fuselage portions can be folded backward on opposite sides of the head portion 15 to form the fuselage, tail, and rudders, and the neck and transverse wing portion can be folded backward from the top of the head portion and secured to the upper edges of the fuselage and tail portions, so as to hold 20 and stiffen the head, wing, fuselage and tail in position to form the complete miniature aeroplane.

In order that my invention may be fully understood, I shall first describe in detail 30 the mode in which I at present prefer to carry this invention into practice, and then particularly point out the invention in the claims.

Reference is to be had to the accompanying drawings forming part of this application 35 for patent in which like parts are designated by the same numbers in all the figures.

Figure 1 is a plan view of the principal blank from which one form of aeroplane embodying my invention is mainly formed.

40 Figure 2 is a plan view of an adjustable blank used with the blank shown in Figure 1 to complete the toy aeroplane.

Figure 3 is a sectional side elevation of the complete toy aeroplane thus formed.

45 Figure 4 is a bow view of the same, part of the wing being broken away.

Figure 5 is a plan view of the same.

Figure 6 is a plan view of the principal blank from which a modification of my invention is formed.

Figure 7 is a plan view of an additional blank used with that shown in Figure 6, to complete the said modified form of aeroplane.

Figure 8 is a sectional side view of the said form completed.

Figure 9 is a bow view of the same.

Figure 10 is a plan view of the same.

Figure 11 is a plan view of the principal blank from which another modification of my invention is formed.

Figure 12 is a plan view of an additional or second blank used with that shown in Figure 11 to complete the aeroplane.

Figure 13 is a plan view of an additional or third blank used with the blanks shown in Figures 11 and 12, to complete the aeroplane.

Figure 14 is a sectional side view of the complete aeroplane formed from the blanks shown in Figures 11, 12, and 13.

Figure 15 is a bow view of the same.

Figure 16 is a plan view of the same.

Referring first to Figures 1, 2, 3, 4, and 5, the principal blank 17, shown in Figure 1 is formed with a transverse wing portion 18, having a medial rear extension 19, with opposite lateral tongues 20, 20' and a transverse slit 21 at the base of the extension 19. From the middle of the front edge of the wing portion 18, extends a narrowed neck portion 22, on opposite sides of which rearwardly extending slits 23 are cut in the wing portion, forming therebetween a rear extension 24 of the neck portion. On the outer sides of the slits 23 are formed forward extensions 25 of the wing portion, and on the forward edges of said extensions 25 are formed propeller extensions 26, with lateral bracket extensions 27, the upper and lower edges of which are preferably curved for a purpose hereafter described.

On the forward end of the neck portion 22, is formed a preferably rectangular head portion 28 formed with diagonal propeller portions 29, and from opposite sides of the head portion 28 project oppositely and laterally combination fuselage and tail portions 30 formed on their upper edges on opposite sides of the head portion with wing portions 31, on their lower edges with leg portions 32, about midway of their length with slits 33, and on

their rear ends with upright rudder portions 34, at the bases of which are cut laterally extending slits 35, and downwardly projecting tongues 36.

5 The additional blank shown in Figure 2, is formed with a longitudinal rearwardly tapering body portion 37 having opposite lateral extensions 38, a forward medial tongue 39, and, on its rear end, a horizontal rudder portion 40, having a medial longitudinal slit 41, and a rear end longitudinal slit 42.

To assemble the aeroplane from the blanks thus described and shown in Figures 1 and 2, the combination fuselage and tail portions are 15 bent rearwardly on the vertical lines 43, connecting them with the head portion 28, so as to converge rearwardly. The neck portion 22 is bent rearwardly on the transverse line 44 connecting it with the head portion 28, and 20 on the transverse line 45 connecting it with its extension 24.

The wing portion 18 is bent rearwardly on the transverse lines 46, connecting it with the propeller portions 26, and on the transverse lines 47, 48, successively to the rear of the line 46, and the rear wing extension 19 is bent downwardly on the transverse line 49 connecting it with the wing portion 18.

30 The tongues 20, 20' on the rear wing extension 19 are then inserted in the respective slits 33 in the fuselage portions 30, so as to secure the wing portion 18 to the fuselage portions 30 and hold both in position.

35 The bracket portions 27 are bent rearwardly on the vertical lines 50, connecting them with the propeller portions 26, and under the front doubly bent portion of the wing, so that the upper curved edges of the bracket portions 27 will uphold and shape the forward bent portion of the wing into a close simulation of that part of the wing of a full-size aeroplane.

40 The lateral extensions 38 of the additional blank shown in Figure 2 are then bent downward on the rearwardly converging lines 51 connecting them with the body portion 37, the forward tongue 39 thereof inserted in the slit 21, in the wing portion, the downwardly bent extensions 38, placed between the rearwardly 45 extending fuselage portions 33, both the upright tail rudder portions 34 inserted in the slit 42, in the horizontal rudder portion 40, and both tongues 36, inserted in the slit 41.

45 The lugs 31 are then bent inwardly over the neck portion 22 which now forms the top of the bow of the fuselage, so as to complete the fuselage.

50 A complete toy aeroplane for display is thus formed, as shown in Figures 3, 4, and 5, which is supported on the legs formed by the leg portions 32, and tail skids formed by skid portions 52 which depend from the lower edges of the fuselage portions 30.

55 The head portion 28 forms the square bow of the aeroplane with the propeller portions

29 simulating one propeller; the doubly bent wing portions forward of the transverse line 48 form the curved surface of the wing; the winged propeller portions 26 simulate the two additional propellers of this type of aeroplane; the body portion 37 of the additional blank forms the closed top of the fuselage, held in place by the downwardly bent lateral extensions 38, the forward tongue 39, the rear tongues 36, and the upright rudder formed by the rudder portions pinched together in the slit 42, and the horizontal rudder portion 40 forms the horizontal rudder.

70 The wing and fuselage are held together and in position by the tongues 20 on the rear wing extension 19, entering the slits 33, and the curved bracket portions 27 supporting the wing, as well as by the bent tongues 31, and the additional blank (Figure 2) bent and fixed in place as described.

75 In the modified form of toy display aeroplane shown in Figures 6, 7, 8, 9, and 10, the winged head portion 53, of the blank shown in Figures 6 and 7, the neck portion 54, its rear extension 55, the transverse wing portion 56, adjoining the neck extension 55, the fuselage portions 57, the upright rudder portions 58, the skid portion 59, the leg portions 60, the upright rudder slits 61 and tongues 62, the additional fuselage blank 63, with its lateral extensions 64, horizontal rudder portion 65, and slits 66 and 67 are substantially the same in form and function, as shown in Figures 1, 2, 3, 4, and 5.

80 In this modification, however, the rear edge of the wing portion 56 is formed with a pair of forwardly extending slits 68, which, when the neck portions 54, wing portion 56, and fuselage portion 57, are bent rearwardly, as described in connection with Figures 1 to 5, are engaged with rearwardly extending slits 69 in the upper edges of the respective fuselage portions 57, so as to secure the wing portion to the fuselage portions and form the wing and fuselage.

85 In this modification, the upper edges of the fuselage portions 57 are formed with curved portions 70, over which the neck extension 55 and the formed portion of the wing portion 56 is bent so as properly to curve and shape the wing, as shown in Figures 8 and 9 which show the aeroplane completed and set up for display purposes.

90 In the modified form of toy aeroplane shown in Figures 11 to 16, the fuselage portions 71, project in opposite sides of the winged square head portion 72, as in the two previously described forms, and are formed with upright rudder portions 73 with slits 74, lugs 75, skid portions 76, and leg portions 77, substantially as in said other forms.

95 In this form of aeroplane however, the wing portion 78, shown in Figure 12, is made from a blank separate from the fuselage portion, and is placed under the forward part of

the completed fuselage as shown in Figures 14, 15, and 16, in simulation of another well-known type of aeroplane.

5 The fuselage portions 71, are formed on either side of the head portion 72 with transverse slits 79; inside the leg portions 77, with slits 80, extending upwardly and rearwardly from the lower edges of the fuselage portions; and outside the leg portion 77, with recesses 10 81 from their lower edges.

In the middle of the wing portion 78, is cut out a tongue 82, and in its lower or rear edge is cut out a tongue 83, leaving between the tongue openings a cross bar 84.

15 The additional fuselage portion 85 shown in Figure 13 is formed with a horizontal rudder portion 86, with a medial slit 87 and rear end slit 88 and with lateral extensions 88, as and to function with the rearwardly folded fuselage 20 portions 71 substantially as previously described in connection with the two other forms previously referred to.

In addition, however, the extra fuselage portion 85, is formed with opposite lateral 25 tabs 89, forward of the extensions 88, to be bent downward and fit inside the rearwardly folded fuselage portions 71; with opposite lateral tabs 90 forward of the tabs 89, to be bent downward and fit inside the fuselage 30 portions 71, with tongues 91 on the ends of the tabs 90, to enter the respective slits 79, and secure the top fuselage portion 85 to the main fuselage portions 71, and with a forward end tab 92 to be bent downward and bear against 35 the head portion 72, as shown in Figure 14.

To secure the wing portion 78 to the completed fuselage thus formed, the forward side of the wing portion is inserted in the opposite slits 80, and the cross-bar 84, inserted in the 40 recesses 81, the tongue 83, being bent downward and resting against the rear ends of said recesses 81 and the legs formed by the leg portions 77, passing downward through the opening of the tongue 82, as best shown in 45 Figure 14.

The wing portion, main fuselage portions and top fuselage portion are thus secured together and in proper position to form a simulation of the special type of aeroplane 50 planned, and make an effective display for advertising purposes.

It is evident that other forms of my invention may be similarly constructed without departing from the boundaries of my invention 55 as defined by the following claims.

I claim as my invention:

1. A flexible blank for forming a toy display aeroplane comprising a medial head portion, fuselage side portions extending laterally and oppositely from the same, adapted to be folded rearwardly therefrom, and having slits therein, and rear end upright rudder portions having slits, a slit transverse wing portion to rest against the folded fuselage side portions and be secured in the side

slits, and a top having a rear slit fuselage portion with a forward tongue to enter the rear slit of the wing, and a rear end horizontal rudder portion to enter the slits in the upright rudder portion, and also receiving 70 the rudder portion in the rear slit.

2. A toy display aeroplane in accord with claim 1, in which the transverse wing portion has a middle rear extension with opposite end tongues to enter the side slits in the 75 respective side fuselage portion.

3. A toy display aeroplane in accord with claim 1, in which laterally extending bracket portions curved on their upper edges, are formed on the forward edges of the wing 80 portion to be bent rearwardly under the wing portion and support and shape the same.

4. A toy display aeroplane in accord with claim 1, in which circular engine and propeller and engine casing portions, the latter 85 curved on their upper edges, are formed on the forward edge of the wing portion to be bent rearwardly under the wing portion and support and shape the same.

5. A flexible blank for forming a toy display aeroplane comprising an unbroken medial head portion, fuselage side portions extending laterally and oppositely therefrom, adapted to be folded rearwardly and having rudder portions on their ends formed 90 with receiving slots and locking projections, a wing adapted to seat transversely over the fuselage in interlocking engagement therewith, and a top fuselage and rudder portion adapted to seat over the fuselage sides in engagement with the slots of the rear rudder portions, and having a slot to receive both locking projections of the rear rudder portions to lock the parts together.

In testimony whereof I affix my signature. 105
JOSEPH EDWIN BURGESS.
